UNITED STATES PATENT OFFICE

161,267

MINIATURE ALTAR

Benjamin A. Johnson, Chicago, Ill.

Application March 25, 1950, Serial No. 8,783

Term of patent 7 years

(Cl. D29—23)

To all whom it may concern:

Be it known that I, Benjamin A. Johnson, a citizen of the United States, residing at 6626 Greenwood Avenue, Chicago 37, Illinois, have invented a new, original, and ornamental Design for a Miniature Altar, of which the following is a specification, reference being had to the accompanying drawing, forming a part hereof.

Fig. 1 is a front elevation view of a miniature altar, showing my new design.

Fig. 2 is a side elevation view of the same.

Fig. 3 is a top plan view of the same.

I claim:

The ornamental design for a miniature altar, substantially as shown.

BENJAMIN A. JOHNSON.
